UNITED STATES PATENT OFFICE.

DAVID W. BOVEE, OF RICHLAND CENTRE, WISCONSIN.

HAY-TEDDER.

SPECIFICATION forming part of Letters Patent No. 289,382, dated December 4, 1883.

Application filed March 31, 1883. (No model.)

To all whom it may concern:

Be it known that I, DAVID W. BOVEE, of Richland Centre, in the county of Richland and State of Wisconsin, have invented certain new and useful Improvements in Hay-Tedders; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved hay-tedder. Fig. 2 is a longitudinal vertical section of the same, and Figs. 3 and 4 are detail views illustrating the construction of certain parts of the machine.

Similar letters of reference indicate corresponding parts in all the figures.

In the accompanying drawings, A designates the frame of the machine, which is mounted upon the axle B, having the wheels C C. D is the tongue, the rear end of which is fastened upon the axle B by a bolt, b, and is provided with hounds or braces E E. The tongue is inserted through a yoke, F, bolted to the front part of the frame, and is provided with a lever, G, having a spring-pawl, H, which is adapted to engage a segmental rack, I, secured upon the front part of the frame. By means of this lever G, in conjunction with the spring-pawl H and segmental rack I, the pitch of the machine may be raised or lowered at will from the driver's seat, which is shown at J. The double-tree K and whiffletrees L are attached to the tongue in the usual manner. Journaled in bearings a, fastened to the under side of frame A, back of the axle, is a shaft, M, having four arms, N, at opposite ends, crossing each other at right angles. In the outer ends of each of these arms are bearings or boxes O, in which the arms N' are hung. These arms are provided with curved teeth P, and are provided on their projecting outer ends with catches Q, which are adapted to engage the offsets R on the semicircular segment S, which is bolted to the under side of the machine, on one or both of the side beams of the same. Each of the boxes O has a slot, n, in which works a pin or projec-

tion, m, which is fastened in the rounded part of arm N', as will be seen more clearly by reference to Fig. 3 of the drawings. This pin or stud m, working in the slot n, limits the play or throw of the rake-arm N', as this is being actuated by the catches Q striking against the offsets R. The side pieces of the frame are connected at the rear end by the clearer-bar T, which has a series of inward projections, t, adapted to fit into the spaces between the rake-teeth P; and shaft M is provided with a pulley, U, which receives a rotary motion from the large pulley V on the drive-wheel by means of an endless band or belt, W.

From the foregoing description, taken in connection with the drawings, the operation of my improved hay-tedder will readily be understood. As the machine advances over the field to scatter the hay for the purpose of exposing it to the air and sunlight, the rake-reel is rotated, and the teeth upon its arms N' are, by its catches Q engaging the offsets R upon the guide-segment S, turned so as to catch the hay and carry it around until the upper part of segment S is reached, when the catch is again released from the guide-segment S, which turns arm N' in such a position as to drop the hay. If any hay should still adhere to the teeth, it will be removed therefrom by the teeth passing between the projections t on the clearer-bar T.

Having thus described my invention, I claim and desire to secure by Letters Patent of the United States—

1. In a hay-tedder, the combination of the frame A, having segmental guide S, provided with offsets R R, the rotary rake-reel having rake-arms N', provided with the pins m, teeth P, and catches Q, and the arms N, provided with the slotted boxes or bearings O, constructed and combined to operate substantially in the manner and for the purpose shown and set forth.

2. In a hay-tedder, the rotary reel consisting of the central shaft, M, having pulley U, arms N, provided with slotted boxes O at their outer ends, arms N', having teeth P, and provided with the pins or studs m, for controlling their play in the slotted boxes, and means for partly rotating the rake-arms in their boxes or

bearings by the revolution of the reel, substantially as and for the purpose shown and set forth.

3. The improved hay-tedder herein shown and described, consisting of the frame A, fixed upon the axle B, and provided with the clearer-bar T at its rear end, tongue D, provided with means for adjusting the pitch or elevation of the front part of the machine, 5 drive-wheels C, having pulley V, endless band W, segmental guide S, provided with the offsets R R, and rotary reel composed of the central shaft, M, having pulley U, arms N, hav-

ing slotted boxes O, and movable rake-arms N, having the pins m, and catches Q, the 15 whole constructed and combined to operate substantially in the manner and for the purpose herein shown and set forth.

In testimony that I claim the foregoing as my own I have hereunto affixed my signature in 20 presence of two witnesses.

DAVID W. BOVEE.
